(57) **CLAIM**

The ornamental design for a trim piece for a trailer, as shown and described.

DESCRIPTION

FIG. 1 is a side elevational view of a trim piece for a trailer showing my new design with the trim piece being provided on a lower portion of the trailer, the trailer being shown in broken lines for illustrative purposes only and forming no part of the claimed design;

FIG. 2 is a side elevational view of a rear section of the trim piece of FIG. 1.

FIG. 3 is a side elevational view of the rear section of the trim piece opposite that shown in FIG. 2.

FIG. 4 is an end view of a front section of the trim piece from the perspective of the front of the trailer.

FIG. 5 is an end view of the rear section of the trim piece from the perspective of the rear of the trailer.

FIG. 6 is a side elevational view of the front section of the trim piece of FIG. 1; and,

FIG. 7 is a side elevational view of the front section of the trim piece opposite that shown in FIG. 6.
